LOOM

Louis J. Zerbee, Bellefontaine, Ohio

Application July 7, 1941, Serial No. 401,333

4 Claims. (Cl. 139—97)

This invention relates to a loom and more particularly to a loom adapted for weaving spring wire into a metallic screen.

An object of this invention is to weave a wire screen from continuous length wires used as the warp, so that the loom may operate continuously night and day without interruption normally caused by winding the warp wires upon a warp drum.

Another object of this invention is to provide a loom that is automatic in its operation, that is easily operated, that is dependable, that weaves steel wire into high quality metallic screen produced cheaply and efficiently.

Other objects and advantages reside in the construction of parts, the combination thereof and the mode of operation, as will become more apparent from the following description.

In the drawing,

Figure 1 is a side elevation of the loom assembly, together with a portion of the warp mill, with parts omitted for the sake of clearness.

Figure 2 is an enlarged sectional view of the tensioning means and a part of the drum.

In the past, looms have been utilized for weaving screen wire from fine wire that is rather soft and flexible. Heavier wire has also been woven; but in weaving heavier wire no automatic shuttle has been used. Instead, the weft has been placed in position manually in most cases, or semi-manually. If put in by the machine or hand, it is pushed through in place of being pulled through. Furthermore, the warp of the metallic screen has been supplied from a drum that is periodically rewound, halting the operation of the loom during the rewinding of the drum. In some cases it has been the practice to operate a loom about half of the time, the other half of the time being utilized in rewinding or rereeling the drum supplying the warp to the loom and threading the warp through the heddles and the reeds.

In the present embodiment, wire screen which may have approximately eight mesh to the inch is woven from high carbon steel wire, so as to form a metallic screen adaptable for use in the manufacture of cushions for steel porch furniture, as disclosed in my Patent No. 2,126,439, patented August 9, 1938. The steel wire used in weaving this metallic screen is comparatively stiff and cannot be woven on the same type of a loom used for weaving fly screen and the like, in that the wires are too heavy and too rigid for manipulation in such looms, which use bobbins on which the weft is wound.

This spring screen is now woven upon a loom that operates automatically and continuously, excepting for short stops to interchange weft coils, in that the warp is supplied from an unlimited source of warp material. Whenever a spool or reel of warp material is exhausted, another spool, having a new supply, is substituted for the old spool by merely butt welding the ends of the wire together. The butt welded joint thus produced is not much thicker than the regular wire, so that the welded wire is fed through the loom without interrupting the operation thereof.

The type of wire is a high carbon manganese steel wire, that is purchased in the form of coils. These coils are first rewound upon spools or bobbins a couple of inches wide and eight to ten inches in diameter. There is one spool or bobbin of warp wire for each strand of warp, these spools being mounted upon a warp mill. From this mill the wires are drawn through a wire tensioning mechanism and wrapped twice around a large drum. After encircling the drum, which drum is actuated so as to supply the wire to the loom at a proper rate of speed, the wires pass through a second tensioning device, through the heddles and the reeds.

Broadly, the loom includes warp wire feeding and manipulating means, a beater, a weft wire source of supply and tensioning device, a weft wire crimping device, a weft feeding device, automatic shuttle driving mechanism, beater driving mechanism and wire snippers or shears, in addition to the usual loom structure, as modified. The structural details and the operation of these various features have been fully described in my copending application Serial No. 287,493, filed July 24, 1939, for Loom, and ripening into United States Letters Patent No. 2,272,456 on February 10, 1942. Only the portion of the loom relating to the warp wire feeding and manipulating means is described herein.

Warp wire feeding and manipulating means

Referring to the drawing, and particularly to Figure 1, the wires 20 form the warp of the web 22 that is woven from high carbon manganese steel wire. Instead of high carbon steel wire, any other spring wire may be used, providing it has the proper resiliency and the other requisites desirable in the manufacture of cushioning devices for use as seats and back rests in porch furniture, chairs, seats and other resilient shock-absorbing devices. The wires 20 are supplied to the loom from spools 24, there being one spool 24 for each wire of the warp. These spools 24 are

removably mounted in a pair of racks 26, only one of which has been shown. These racks 26 are arranged to the rear of the loom and extend in parallel relation. Furthermore, the amount of wire on each spool differs, so that the wire from one spool alone becomes exhausted at one time. When the wire on one spool is nearly exhausted, the spool is removed from the rack 26 and a new spool substituted therefor. The end of the wire on the old spool and the free end of the wire on the new spool are butt welded. In Figure 1 the gripper jaws or terminals 120 are used to schematically illustrate the electric terminals of a butt-welding device. One pair of terminals 120 engages the trailing end 20a of the wire in the loom and the other pair of terminals 120 engages the leading end 20b of the wire of a new spool that is being substituted for an exhausted spool. It has been found that the butt welded wires pass through the loom without difficulty, as the wire where it has been welded is not much thicker than the regular thickness of the wire. By mounting the spools in two racks and mounting the racks in spaced relation from each other at the rear of the loom, a path is formed between the wires passing from the spools to the loom, which permits the attendant to replace or substitute new spools as the old ones are exhausted.

The wires 20 constituting the warp are passed through a tensioning device that includes a plurality of transversely disposed bars 30 and tensioning bar 31, cooperating with a tensioning member 32 clamped in position by suitable adjusting screws 34 to tension the wire as it advances from the spools. From the bars 30 and the tensioning member 32, each wire is wrapped twice around the drum 36 and then through a second tensioning device including transversely disposed bars 38 and a pair of tensioning members 40 and 41 clamped in position by screws 42. The drum 36 is driven through a chain of gears 44, only one gear of which is shown, from a suitable source of power not shown.

The tensioning members 30, 31, 32, 38, 40 and 41 are mounted in close proximity to the drum. These tensioning members function as guides for the wires, preventing the wires from creeping on the drum, in spite of the fact that the drum is coated with an abrasive material. This causes an endwise thrust of the drum, which is resisted by the frame of the loom.

The driving mechanism is so arranged that the angular displacement of the drum during each cycle of operation of the loom is equal to the length of wire extending between the centers of the weft wires. If, for example, an eight mesh screen is woven, that is, eight meshes to the inch, the periphery of the drum is rotated approximately one-eighth of an inch during each cycle of the operation of the loom. The warp wires being wrapped twice around the drum and properly tensioned are advanced a distance equal to the peripheral movement of the drum. The double wrapping of each wire 20 about the drum creates sufficient surface friction so as to cause the wires to move in unison with the drum, no faster and no slower. The mechanism of the loom will, of course, tend to pull the wires away from the drum, as will appear more fully later. The wires forming the warp of the web advance from the transversely disposed bars 38 through two groups of heddles 54 and 56. The heddles 54 and 56, as is well known to those skilled in the art, are supported by a flexible chain, cable or other suitable flexible member 58, extending

over a pulley or sprocket 60 journaled in standards 70, one on either side of the loom. The heddles are reciprocated in a vertical direction by a pair of cams 72 and 74 mounted upon a shaft 76, journaled in the sides of the frame of the loom, through a pair of levers 78 and 80, each having one end pivoted to the frame of the loom.

Beater

Thus far the portion of the loom and parts associated therewith are used primarily in supplying the warp wires. In addition to the warp wires, it is necessary to supply the weft wires in proper relation with respect to the manipulation of the warp wires. Due to the rigidity and the stiffness of the spring wire used, it is necessary to form or crimp the weft wire before it is woven into the material. The warp wires need not be crimped, as the separation of the warp wires to form the shed, in cooperation with the operation of the beater, automatically crimps or forms the warp wires. The crimping mechanism for the weft wire, the severing device and the automatic weft feeding device are all associated with and mounted upon the beater frame.

The standards 70 support a transversely disposed shaft 100, supporting a pair of rocker arms 102, only one of which is shown. These rocker arms 102 support a pair of angle irons 106 and 108 transversely disposed with respect to the loom. These angle irons support the reed elements 110, shown schematically, forming the beater. There is one reed element between each pair of adjacent warp wires.

Beater driving mechanism

The beater, which includes a plurality of reeds 110 spanning the distance between angle irons 106 and 108, is actuated through a pair of links 402, only one of which is shown in Figure 1, having their forward ends pivotally attached to the upright members 102 and the rear ends attached to a pair of crank arms 404, one on each end of the shaft 406 journaled in the frame of the loom and driven in synchronism with the shaft 76. The shaft 406 rotates at twice the speed of the shaft 76, as the shaft 76 rotates once for one complete cycle of the operation of the loom, during which cycle the beater reciprocates twice, so as to position two succeeding weft wires, as is well known to those skilled in the art.

As the beater reciprocates to position the weft wires in the shed, the beater exerts a pull upon the warp wires, so as to pull the warp wires through the second tensioning mechanism located between the beater and the drum 36. Thus, it is seen that there is one tensioning device, including members 31 and 32, that tensions the warp wires before the warp wires advance to the drum and there is a second tensioning device that tensions the wires after they leave the drum.

Mode of operation

After the warp wires have been properly threaded or strung through the loom and a coil of weft wire has been mounted in position with an end projecting through the crimping rollers, the driving motor, which has not been shown, may be started. This motor drives the drum 36 at a rate of speed compatible with the mesh of the screen to be woven. As the surface of the drum 36 may be of metal or of wood, slippage of the warp wires is prevented by suitable abrasive or friction producing means. The abrasive material may be applied by covering the periphery

of the drum with sheets of abrasive material, or the periphery of the drum may be painted or covered with suitable cement having embedded therein emery or abrasive material, causing a positive drive between the drum and the warp wires.

The warp wires on the spools 24 are of unequal lengths, so that the warp wires become exhausted at different times. When the warp wire on one spool is practically exhausted, the remaining portion of the warp wire is unwound, the spool is removed, a new spool inserted and the end of the wire of the exhausted spool and the end of the wire of the new spool are butt welded, without stopping the loom and without interrupting the operation thereof. As far as the warp wires are concerned, the loom may operate continuously without interruption, the butt weld being of such dimensions that it will pass through the loom without interference.

Instead of rewinding the steel wire upon spools or ribbons, the coils of wire as received from the factory may be inserted upon proper dispensing reels or supports, there being one coil for each warp wire.

Although the preferred modification of the device has been described, it will be understood that within the purview of this invention various changes may be made in the form, the combination thereof and mode of operation, which generally stated consist in a device capable of carrying out the objects set forth as disclosed and defined in the appended claims.

Having thus described my invention, I claim:

1. A wire feeding mechanism for use in a loom having a beater, said wire feeding mechanism including a drum mounted for rotation, means for rotating said drum so that its upper surface moves in the same direction as the warp wires are fed, means for supplying relatively stiff carbon steel wires to the drum, each warp wire being wound at least twice around the periphery of the drum, and tension means for the wires, said tension means being located between the drum and the beater of the loom.

2. A wire feeding mechanism for use in a loom having a beater, said wire feeding mechanism including a drum mounted for rotation, means for rotating said drum so that its upper surface moves in the same direction as the warp wires are fed, means for supplying relatively stiff carbon steel wires to the drum, each warp wire being wound at least twice around the periphery of the

drum, and a pair of tensioning means for the wires, one of said tensioning means being located between the wire supplying means and the drum, and the other tensioning means being located between the drum and the beater of the loom.

3. In a loom for weaving a metallic screen from continuous length warp wires obtained by butt welding the trailing end of one spool to the free end of another, the combination including a plurality of supports, a plurality of spools mounted upon said supports, there being one spool for each warp wire, said spools having unequal lengths of warp wire, means for releasably supporting the spools on said supports so that as the wire on one spool becomes exhausted another spool with a fresh supply of warp wire may be substituted for the exhausted spool, the trailing end of the wire from the exhausted spool being butt welded to the free end of the substituted spool, and wire feeding means for positively feeding the warp wires from the spools to the loom, said wire feeding means including a drum around which each warp wire is wound at least twice, means for driving the drum so that its upper surface moves in the same direction as the warp wires are fed, each warp wire being wound at least twice around the periphery of the drum, and tension means for the wires, said tension means being located between the drum and the beater of the loom.

4. In a loom for weaving a metallic screen from continuous length warp wires, the combination including a plurality of coils of warp wires obtained by butt welding the trailing end of one spool to the free end of another, means for releasably supporting the coils so that as the wire of one coil becomes exhausted another coil with a fresh supply of warp wire may be substituted for the exhausted coil, the trailing end of the wire from the exhausted coil being butt welded to the free end of the substituted coil, wire feeding means for positively feeding the warp wires from the coils to the loom in synchronism with the operation thereof, said last mentioned means including a drum mounted for rotation, means for driving the drum so that its upper surface moves in the same direction as the warp wires are fed, each warp wire being wound at least twice around the periphery of the drum, and tension means for the wires, said tension means being located between the drum and beater of the loom.

LOUIS J. ZERBEE.

CERTIFICATE OF CORRECTION.

Patent No. 2,383,903.

August 28, 1945.

LOUIS J. ZERBEE.

It is hereby certified that error appears in the printed specification of the above numbered patent requiring correction as follows: Page 3, first column, line 22, for "ribbons" read --bobbins--; and that the said Letters Patent should be read with this correction therein that the same may conform to the record of the case in the Patent Office.

Signed and sealed this 29th day of January, A. D. 1946.

Leslie Frazer

(Seal) First Assistant Commissioner of Patents.
